CIRCUIT INTERRUPTER

Winthrop M. Leeds, Wilkinsburg, and Benjamin P. Baker, Turtle Creek, Pa., assignors to Westinghouse Electric Corporation, East Pittsburgh, Pa., a corporation of Pennsylvania

Application September 17, 1942, Serial No. 458,660

8 Claims. (Cl. 200—150)

This invention relates to circuit interrupters in general and, more particularly, to circuit interrupters which effect arc extinction by a blast of arc extinguishing fluid.

Certain features of the invention are described and claimed in applicants' divisional application, filed January 27, 1945, Serial Number 574,856, entitled "Circuit interrupters" and assigned to the assignee of the instant application.

An object of the present invention is to provide an improved arc extinguishing structure in which a pressure generating arc and an interrupting arc are established and which provides a more effective flow of arc extinguishing fluid from said pressure generating arc to said interrupting arc to effectively quench the latter.

Another object is to provide an improved contact structure in which flexible current carrying shunts are avoided and in which a single biasing means serves to not only bias a cooperating contact away from the stationary contact, but also to provide the desired contact pressure when the stationary and cooperating contacts are in abutting relation.

Another object is to provide an improved intermediate contact structure in which a single compression spring not only biases the intermediate contact away from the stationary contact when the breaker is in the open circuit position, but also furnishes the requisite contact pressure in the closed circuit position.

Another object is to provide an improved circuit interrupter in which the intermediate contact is successively pivotal about two fulcrum points.

Another object is to provide an improved interrupting structure in which a concentrated blast of fluid is employed both for rapid arc lengthening and for scavenging purposes.

Another more specific object is to provide an improved circuit interrupter in which an arc is established, and in which a fluid blast is concentrated and directed against the initially formed portion of said arc which tends to lengthen the same at a greater rate than the rate of separation of the movable contacts, and to provide means to prevent such lengthening until relatively low instantaneous values of arcing current. It will be readily apparent that such a concentrated fluid blast will build up the dielectric strength in the relatively short gap between the contacts to prevent restriking in this region after the greatly lengthened arc itself has been extinguished.

The term "fluid" as used in the specification

and in the appended claims includes gases, liquids and vapors.

It will be readily apparent to one skilled in the art that our invention is applicable to circuit interrupters operating in gaseous mediums, such as air, as well as in liquid mediums. However, for purposes of illustration, and not by way of limitation, we illustrate our invention as applied to circuit interrupters of the liquid immersed type.

Further objects and advantages will become apparent upon a reading of the following specification taken in conjunction with the drawings, in which:

15 Figure 1 is an elevational view, partly in cross section, of a circuit interrupter embodying our invention;

Fig. 2 is an enlarged fragmentary elevational view, partly in cross section, of one of the arc extinguishing structures shown in Fig. 1;

Fig. 3 is a plan view in cross section taken on the line 3—3 of Fig. 2;

Fig. 4 is an inverted plan view in cross section taken on the line 4—4 of Fig. 2;

25 Figs. 5 through 12 are plan and side views of plates used in the arc extinguishing structure of Fig. 2;

Figs. 13 and 14 are enlarged fragmentary elevational views showing various positions of the intermediate contact of Fig. 2;

Fig. 15 is an enlarged elevational view in cross section through another circuit interrupting structure embodying our invention;

Fig. 16 is a plan view in cross section taken on the line XVI—XVI of Fig. 15;

Fig. 17 is a plan view in cross section of a circuit interrupting structure, not shown, but similar to the circuit interrupting structure of Fig. 15, illustrating a further embodiment of our invention;

Figs. 18 through 20 illustrate various intermediate positions of the intermediate contact used in the interrupting structure of Fig. 15;

45 Figs. 21 through 24 show various positions of a different intermediate contact structure which may be employed in any of the circuit interrupting structures shown in the drawings; and

Figs. 25 through 36 show enlarged plan and side views of insulating plates used in the interrupting structures shown in Figs. 15 and 17.

Referring to the drawings, and more particularly to Figure 1, the reference numeral 1 designates a tank filled with a suitable arc extinguishing liquid 2, such as oil, in which are immersed a

plurality, in this instance two, arc extinguishing structures 3 supported by the two stationary contact structures 4 and the insulating bushings 5 in a conventional manner. An insulating operating rod 6, carrying at its lower end a conducting bridging member 7, is adapted for longitudinal reciprocating motion through the cover 8 of the tank 1 and operated by an external operating mechanism, not shown, to effect the opening and closing of the circuit interrupter. It will be apparent that the circuit interrupter is connected into the external circuit by the line terminals 9. Hence the electrical circuit through the interrupter consists briefly of the left hand line terminal 9, the left hand stationary contact structure 4, the conducting bridging member 7, the right hand stationary contact structure 4 and the right hand line terminal 9 as viewed in Fig. 1.

The dot and dash lines designated by the reference numeral 10 indicate the position of the conducting bridging member 7 when the circuit interrupter is in the open circuit position.

Referring to Fig. 2, which shows an enlarged elevational view in cross section of the left hand arc extinguishing structure 3 shown in Fig. 1, it will be observed that there is provided a stationary contact 11, an intermediate contact structure generally designated by the reference numeral 12 and a lower movable contact 13 constituting the upstanding portion of the conducting bridging member 7. When the circuit interrupter is to be closed the conducting bridging member 7 is raised by the insulating operating rod 6 to bring the movable contact 13 upward to engage the intermediate contact structure 12 in a manner shown in Fig. 14.

The intermediate contact structure 12 comprises a lever 14, at the left hand end of which is a contacting portion 15 which is adapted to engage the stationary contact 11. At the right hand end of the lever 14 is secured a pin 16 which operates in slots 17 provided in upstanding brackets 18. A stud 19, rigidly secured to an insulating plate 20 with a cap 21 at its upper end, carries a compression spring 22 which serves to bias the lever 14 downward away from the stationary contact 11. A contacting portion 23 of the lever 14 engages the movable contact 13 in the closed circuit position of the interrupter as shown more clearly in Fig. 13.

It will be apparent that upward motion of the movable contact 13 will produce abutting engagement between the movable contact 13 and the contact portion 23 of the lever 14 to first cause a clockwise rotation of the lever 14 about the pin 16 when the pin 16 is at the lower end of the slots 17 as more clearly shown in Fig. 14. This clockwise rotation of the lever 14 continues until the contact portion 15 strikes the stationary contact 11, at which time the lever 14 rotates in a counterclockwise direction about the stationary contact 11 as a pivot point until the pin 16 nearly reaches the top of the slots 17 as clearly shown in Fig. 13.

When it is desired to open the interrupter the movable contact 13 is drawn downward to permit a clockwise rotation of the lever 14 about the stationary contact 11 as a fulcrum point until the pin 16 reaches the lower end of the slots 17, at which time the lever 14 begins a counterclockwise rotation about the pin 16 as a fulcrum point until the lever 14 rests on the insulating plate 20. At this point in the opening operation the movable contact 13 withdraws from the

contacting portion 23 of the intermediate contact structure 12.

It will be apparent that upon opening of the breaker under load a pressure generating arc 24 will be drawn between the stationary contact 11 and the contact portion 15 of the lever 14. Further opening movement will draw an interrupting arc 25 between the contact portion 23 of the lever 14 and the movable contact 13.

The interrupting arc 25 is drawn in an interrupting structure comprising a plurality of suitably shaped insulating plates held together by the insulating studs 26. The insulating plates form a pressure generating chamber 27, a conduit generally designated by the reference numeral 28, a plurality of flow passages 29, an arc slot generally designated by the reference numeral 30, a very restricted arcing slot 31 and a plurality of vent passages 32.

Referring more particularly to Figs. 5 through 12, the reference numeral 33 (see Figs. 9 and 10) designates an insulating insert plate formed with a plurality of apertures 34 for the reception of the insulating studs 26, an aperture 35, a relatively widened slot 36 which communicates with an adjacently disposed relatively narrow slot 37 and a U-shaped insert 38 of magnetic material, such as iron, the purpose for which will appear more clearly hereinafter.

Immediately above and below the insert plate 33 is a guard plate 39 (see Figs. 7 and 8) also composed of insulating material having the same configuration as the insert plate 33 and having the function of protecting the U-shaped magnetic insert 38 from the interrupting arc 25. Adjacent to the insulating guard plates 39 are a plurality, in this instance three, pocket plates 40 containing apertures 34 for the reception of the insulating studs 26 and also having an enlarged aperture 41 which communicates by passage 42 with a plurality, in this instance four, pockets 43, as more clearly shown in Figs. 5 and 6. A vent passage 44 connects the right hand pocket 43, as viewed in Fig. 5, to the region outside of the pocket plate 40.

The bottom plate in the stack is designated by the reference numeral 45 and is more clearly shown in Figs. 11 and 12. It is formed of insulating material and contains apertures 34 for the reception of the insulating studs 26 and also has formed therein an elongated slot 46 to accommodate the motion of the movable contact 13. The elongated slot 46 is beveled at 47 to facilitate the guiding of the movable contact 13 during the closing operation of the breaker.

When the several insulating plates are assembled on the insulating studs 26 they will form the pressure generating chamber 27, the conduit 28, the plurality of flow passages 29, the relatively wide arcing slot 30, the plurality of relatively narrow arcing slots 31 and a plurality of vent passages 32. When the circuit interrupter is opened the pressure generating arc 24 will react upon the oil disposed in the pressure generating chamber 27 to close the check valve 48 (see Fig. 2) and to force oil through the conduit 28, through the plurality of flow passages 29 (the movable contact 13 not serving as a valve to close off the flow passages 29), through the relatively widened arcing slot 30, and out through the vent passages 32.

During relatively high instantaneous values of arcing current the cross section of the interrupting arc 25 will be too large to permit it to be forced into the relatively narrow arcing slots 31,

although the flow of oil through the flow passages 29 will tend to carry the interrupting arc 25 to the right toward the vent passages 32. The magnetic inserts 38 will bias the interrupting arc 25 to the left, as viewed in Fig. 2, with a force approximately proportional to the square of the instantaneous value of arcing current through the interrupting arc 25. During this time when the interrupting arc 25 is biased by the magnetic inserts 38 away from the relatively narrow restricted arcing slots 31 the flow of oil through the flow passages 29 will be such as to freely pass by on both sides of the arc column, since the passage 42 in the pocket plates 40 (see Fig. 5) is sufficiently wide to permit a relatively free passage of oil past the interrupting arc 25 and out through the vent passages 32.

When, however, the instantaneous value of arcing current through the interrupting arc 25 falls to a relatively low value, that is, approaching a current zero on the alternating current wave, the magnetic biasing force exerted toward the left by the magnetic inserts 38 will correspondingly decrease to permit the oil flow through the flow passages 29 to carry the interrupting arc 25 into the plurality of constricted arcing slots 31 where it will be blasted by a transverse flow of oil and gas particles to effect its extinction. It will be noticed that during relatively low instantaneous values of arcing current the cross section of the interrupting arc 25 will be sufficiently small to permit it to be forced into the constricted arcing slots 31 where it is held in a centralized and relatively fixed position to be effectively acted upon by the flow of oil and gas particles.

It will be observed that the method of arc extinction thus far described disturbs the continuity of the interrupting arc 25 very little during the peak of the alternating current wave, yet brings into play effective deionizing conditions at or near a current zero when extinction is most easily effected.

It will be noted that in the provision of the particular intermediate contact structure 12 described a number of advantages result. First, there is a rolling motion between the movable contact 13 and the contact portion 23 of the lever 14 to prevent any welding between the movable contact 13 and the contact portion 23. The rolling motion is also present between the stationary contact 11 and the contact portion 15 of the lever 14. No flexible shunts are necessary, the current passing directly from the movable contact 13 through the contacting portion 23, the lever 14, the contacting portion 15 to the stationary contact 11, the latter being preferably fixed in position. The particular arrangement of the compression spring 22 eliminates the necessity for resiliently mounting the stationary contact 11 since the compression spring 22 produces the desired contact pressure and takes up the shock on closing.

It will be observed that the pockets 43 located in the pocket plates 40 (see Fig. 5) provide a plentiful supply of arc extinguishing liquid adjacent the widened arcing slot 30 and also adjacent the relatively narrow arcing slots 31 which may be acted upon by the interrupting arc 25 to provide additional transverse blasts of oil and gas particles.

In the open circuit position of the interrupter, shown by the dotted lines 10 in Fig. 1, the movable contact 13 is withdrawn from the arc extinguishing structure 3 to provide an isolating break. Also, fresh arc extinguishing liquid is

thus permitted to enter the enlarged slot 46 in the bottom insulating plate 45 (see Fig. 11), through the vent passage 32 and through the check valve 48 to provide a fresh supply of arc extinguishing liquid for the next circuit opening operation of the circuit interrupter.

Some features of the above method of arc extinction are described and broadly claimed in Patent 2,138,382 which issued November 29, 1938 to Winthrop M. Leeds and Ennio Ortensi and which was assigned to the Westinghouse Electric & Manufacturing Company.

In the interrupter shown in Fig. 15 a pressure generating arc 77 (see Fig. 18) is drawn between the stationary contact 78 and the upper contacting portion 79 of the intermediate contact structure generally designated by the reference numeral 80. The intermediate contact structure 80 comprises a U-shaped bracket 81 rigidly secured to a metallic support plate 82 by screws 83 (see Fig. 20). The U-shaped bracket 81 serves as an upper seat for a compression spring 84, the lower end of which is seated in a recess 85 provided in the intermediate contact 86 to bias the latter towards its lower position as more clearly shown in Fig. 19. The right hand end of the intermediate contact 86 is pivotally mounted by a pin 87 which is movable in slots 88 provided in two upstanding brackets 89 also rigidly secured to the metallic support plate 82. The movable contact 13 engages a lower contacting portion 90 of the intermediate contact 86.

Referring to Fig. 15, which shows the interrupter in the closed circuit position, it will be apparent that downward motion of the movable contact 13 will result in the intermediate contact 86 pivoting about the stationary contact 78 as a first fulcrum point while the pin 87 moves down in the slots 88 by the biasing action exerted by the compression spring 84. This movement continues until the pin 87 reaches the lower end of the slots 88, at which time the intermediate contact 86 rotates in a counterclockwise direction about the pin 87 as a second fulcrum point, as more clearly shown in Fig. 18. When the intermediate contact 86 has rotated sufficiently in a counterclockwise direction about the pin 87 so that it strikes the metallic support plate 82, continued downward movement of the movable contact 13 draws an interrupting arc 91 as more clearly shown in Fig. 19.

It will be observed that with the intermediate contact structure 80 shown there is no need for flexible shunts, a rolling action between the contact surfaces prevents welding, and a single compression spring 84 provides not only a biasing means to bias the intermediate contact structure 80 to its open circuit position, but also provides contact pressure for the contacts in the closed circuit position. It will further be noticed that both in the intermediate contact structure 12 in Fig. 2 and 80 in Fig. 15 the construction is such that the motion of the intermediate contact substantially prevents fluid flow between the pressure generating chamber and the interrupting chamber other than by the fluid conduits provided.

For example, in Fig. 15 the lower contacting portion 90 substantially fills the slot 92 provided in the insulating partition 93 separating the pressure generating chamber 94 from the interrupting chamber 95.

An alternative intermediate contact arrangement which may be used either in the inter-

rupter shown in Fig. 15 or in any of the other interrupters shown in the drawings is the construction shown in Figs. 21 through 24. Referring more particularly to Figs. 21 through 24, it will be observed that we have provided a U-shaped upstanding bracket 96 which serves as an upper seat for compression springs 97, the lower end of which are seated in a recess 98 provided in the intermediate contact 99. The intermediate contact 99 is pivotally supported by a pin 100 to two links 101 which are pivotally mounted at their left hand ends by the pins 102, 103 to the U-shaped bracket 96 (see Fig. 24).

It will be apparent that the pin 100 is analogous to the pin 87 in Fig. 15, but instead of being guided in the slots 88 as was the case in Fig. 15 the pin 100 is guided by the links 101. The movement of the intermediate contact 99 is the same as the movement of the intermediate contact 86 in the intermediate contact structure 80 shown in Fig. 15; that is, upward movement of the movable contact 13 first causes it to engage the lower contacting portion 104 of the intermediate contact 99 to cause a clockwise rotation of the intermediate contact 99 about the pin 100 as a fulcrum until the contact portion 105 of the intermediate contact 99 engages the stationary contact 106.

Further upward motion of the movable contact 13 causes a counterclockwise rotation of the intermediate contact 99 about the stationary contact 106 as a fulcrum and further compressing the compression springs 97 to produce the desired final contact pressure. Again all flexible shunts can be eliminated, the rolling motion between the contact surfaces prevents welding and a single compression spring serves the dual purpose of an opening biasing means and also as a contact pressure maintaining means. The lower contacting portion 104 substantially fills the slot 108 in the insulating partition plate 109 to prevent fluid flow through the slot 108, thus rendering more effective the fluid flow through the conduit provided for connecting the pressure generating chamber with the interrupting chamber.

Referring particularly to the interrupter shown in Fig. 15 it will be observed that the pressure generating arc 71 (see Fig. 18) creates pressure in the pressure generating chamber 94 to cause fluid flow through the conduit 110 into the interrupting chamber 95 and out the vent passages 111.

An insert insulating plate 112 having the configuration shown in Fig. 33 is provided. The insulating insert plate 112 contains apertures 34 for the reception of the insulating studs 26 and an elongated slot 113, the right hand end of which narrows to a constriction 114. A U-shaped insert 115 composed of magnetic material, in this instance iron, is imbedded in the insulating insert plate 112. Immediately above and below each insulating insert plate 112 is an insulating guard plate 116 having the same configuration as the insulating insert plate 112 and shown more clearly in Fig. 29.

The purpose of the insulating guard plate 116 is to protect the magnetic insert 115 from the action of the interrupting arc 91 drawn in the interrupting chamber 95. Adjacent each insulating guard plate 116 are a plurality, in this instance three, insulating vent plates 117 the configuration of which is more clearly shown in Fig. 25. It will be observed that each insulating vent plate 117 contains apertures 34 for the re-

ception of the insulating studs 26 and an enlarged slot 118 which narrows at 119 and leads to a vent opening 120. When the several insulating plates are assembled on the insulating studs 26 the interrupting arc 91 will be established in an elongated arcing slot generally designated by the reference numeral 121 in Fig. 16.

The several plates in the lower portion of the interrupting chamber 95 are in the same grouping as those in the upper portion of the interrupting chamber 95 and are similar in configuration except that the slots 113 and 118 in these lower plates terminate adjacent the movable contact 13 to concentrate and direct the blast from the conduit 110 between the main contacts.

The operation of the interrupter shown in Fig. 15 will now be explained. When it is desired to open the interrupter the movable contact 13 is moved downward to permit the intermediate contact 86 to rotate in a clockwise direction about the stationary contact 78 as a fulcrum until the pin 87 strikes the bottom of the slots 88, at which time the intermediate contact 86 rotates in a counterclockwise direction about the pin 87 as a fulcrum until the intermediate contact 86 strikes the metallic support plate 82. When this occurs the movable contact 13 will separate from the lower contacting portion 90 to draw an interrupting arc 91 (see Fig. 19). The interrupting arc 91 will be drawn in the elongated arcing slot 121 (see Fig. 16) where it will be acted upon by two forces. One of the forces will be the concentrated oil flow from the pressure generating chamber 94 through the conduit 110 and into the elongated arcing slot 121 toward the vent passages 111.

The other force will be the magnetic biasing force exerted by the magnetic inserts 115 tending to cause the interrupting arc 91 to move to the left, as viewed in Fig. 15, during relatively high instantaneous values of arcing current. It will therefore be apparent that during the peak of the alternating current wave the interrupting arc 91 will be biased away from the constriction 114 provided in the insulating guard plates 116 (see Fig. 29) and the insulating insert plates 112 (see Fig. 33) to permit a relatively free passing of oil past the interrupting arc 91 while it is in the enlarged portion of the elongated arcing slot 121.

When the instantaneous value of arcing current falls to a relatively low value the magnetic biasing force exerted toward the left by the magnetic inserts 115 will correspondingly decrease to permit the concentrated fluid blast through the conduit 110 to carry the interrupting arc 91 to the right as viewed in Fig. 15 to position it in the constriction 114 provided in the insulating guard plates 116 and insulating insert plates 112. It will be noted that the portion 91a (see Fig. 15) of the lower plates causes a concentrated directed blast of oil from the conduit 110 to move the lower terminal of the interrupting arc 91 down the side of the movable contact 13 to rapidly lengthen the same during low instantaneous values of arcing current. In this position the interrupting arc 91 is subjected to very effective extinguishing conditions caused by the liquid and gas flow through the narrowing portion 119 provided in the vent plates 117 (see Fig. 25). It will be observed that the interrupting arc 91 is held in a relatively fixed position at the constriction 114 where the fluid flow tends to converge on the arc because of the narrowing

portion 119 provided in the vent plates 117, this occurring at or near a current zero when the magnetic biasing force exerted by the magnetic inserts 115 is relatively small. Extinction of the interrupting arc 91 soon follows, and the movable contact 13 is withdrawn from the interrupting structure to effect an isolating gap. In the open circuit position fresh oil enters through the vent passages 111 and through the slot 122 in the bottom insulating plate 122a through which the movable contact 13 was drawn. It will be noted that the concentrated and directed blast of oil through the conduit 110 scavenges the relatively short distance between the movable contact 13 and the contacting portion 99 to prevent restriking in the relatively short gap after the relatively lengthened arc 91 has been extinguished.

Fig. 17 shows a modified construction of the interrupter shown in Fig. 15. Fig. 17 represents a plan view in cross section of an interrupter similar to that just described in connection with Fig. 15 except that the conduit 110 in the insulating plate 93 is omitted and in its place longitudinal passages 123 (see Fig. 17) are provided in each plate making up the lower portion of the modified arc extinguishing structure. Fig. 35 illustrates the type of insulating insert plate which may be used in such a modified construction and is represented by the reference numeral 124. The insulating insert plate 124 has openings 125 to form the passages 123 shown in Fig. 17. Insulating plate 124 also contains apertures 34 to accommodate the insulating studs 26, an elongated slot 113 and a constriction 114. An insert 126 composed of a suitable magnetic material, in this instance iron, is formed to such a shape as to accommodate the openings 125. Immediately above and below the insulating insert plate 124 is an insulating guard plate 127, the configuration of which is more clearly shown in Fig. 31. The insulating guard plate 127 contains apertures 34 for the insulating studs 26, openings 125, an elongated slot 113 and a constriction 114. Again the insulating guard plate 127 protects the insulating insert plate 124 from the effect of the interrupting arc. Immediately adjacent to each insulating guard plate 127 is an insulating flow plate 128, the configuration of which is more clearly shown in Fig. 27. This insulating flow plate 128 is similar to the vent plate 117 shown in Fig. 25 except that it contains flow passages 129 which lead from the openings 125 to the enlarged slot 118.

It will be apparent that with the conduit 110 (see Fig. 15) omitted the oil flow from the pressure generating chamber 94 (see Fig. 15) will flow down through the passage 123 and only the flow plates 128 will permit flow into the enlarged slot 118 provided in the flow plates 128. During the peak of the alternating current wave the interrupting arc 91 (see Fig. 19) will be drawn to the left, as viewed in Fig. 17, to a position where the flow coming through the flow passages 129 in the flow plates 128 (see Fig. 27) interferes very little with the continuity of the interrupting arc 91. This reduces the arc energy and internal pressure in the arc extinguishing structure. When, however, the instantaneous value of arcing current falls to a relatively low value, the magnetic inserts 126 will exert little biasing force on the interrupting arc 91 and will permit it to return to the place where it was initially drawn, that is between the opposed flow passages 129 (see Fig. 17) at which position it

receives the full effect of a transverse flow of oil which tends to carry the interrupting arc 91 to the right, as viewed in Fig. 17, to the constriction 114, the flow converging on the interrupting arc 91 in this position as defined by the narrow portion 119 in the flow plates 128. The strong deionizing action in the arc space effectively builds up dielectric strength at current zero so that the arc cannot restrike, thus interrupting the circuit.

It will be apparent to one skilled in the art that our invention is readily applicable not only to liquid immersed circuit interrupters but also to circuit interrupters operating in a gaseous medium, such as air. The insulating plates described in connection with the various embodiments of our invention may be made of a suitable gas evolving material to facilitate the interruption of the interrupting arc. Consequently, any of the interrupters previously described could be operated in air with the insulating plates composed of a suitable gas evolving material such as horn fiber or boric acid. Merely for purposes of illustration, and not by way of limitation, we have described our invention as embodied in various forms of oil immersed circuit interrupters.

The broader aspects of holding an interrupting arc by magnetic means away from vents provided along an elongated arcing slot during the peak of the alternating current wave is described and broadly claimed in a patent application filed March 19, 1942, Serial No. 435,380, by Benjamin P. Baker, now Patent 2,303,524 which issued December 1, 1942 which was assigned to the assignee of the instant application.

Although we have shown and described specific structures, it is to be understood that the same were only for purposes of illustration and that changes and modifications may be made therein by those skilled in the art without departing from the spirit and scope of the appended claims.

We claim as our invention:

1. In a circuit interrupter, a stationary contact, an intermediate contact, a movable contact, said intermediate contact comprising a lever member having a first fulcrum point operative before said intermediate contact engages said stationary contact, said lever member also having a second fulcrum point at said stationary contact during the final closing operation, and the movable contact causing the actuation of the intermediate contact.

2. In a circuit interrupter, a first contact, a second contact cooperable with the first contact, the second contact comprising a lever member successively pivotal about both its ends during the closing operation, and a third contact cooperable with the second contact.

3. In a circuit interrupter, a first contact, a second contact cooperable with the first contact, the second contact comprising a lever member successively pivotal about both its ends during the closing operation, a third contact cooperable with the second contact, and biasing means acting on the lever member intermediate the ends thereof.

4. In a circuit interrupter, a relatively stationary contact, a relatively movable contact cooperable with the relatively stationary contact, the relatively movable contact comprising a lever member having a first fulcrum point operative before the relatively movable contact engages the relatively stationary contact, the lever member also having a second fulcrum point at the relatively stationary contact during the final

closing operation, and a second movable contact cooperable with the relatively movable contact.

5. In a circuit interrupter, a relatively stationary contact, a relatively movable contact cooperable with the relatively stationary contact, the relatively movable contact comprising a lever member having a first fulcrum point operative before the relatively movable contact engages the relatively stationary contact, the lever member also having a second fulcrum point at the relatively stationary contact during the final closing operation, a second movable contact cooperable with the relatively movable contact, and biasing means acting on the lever member intermediate the ends thereof.

6. In a circuit interrupter, relatively stationary contact means, movable lever-shaped contact means pivotally mounted, a second movable contact cooperable with the first-mentioned movable contact, and a single biasing means to bias the movable lever-shaped contact means away from the relatively stationary contact means in the open circuit position of the interrupter, the single biasing means also serving to maintain pressure between the relatively stationary contact means and the movable lever-shaped contact means in the closed circuit position of the interrupter.

7. In a circuit interrupter, relatively stationary contact means, movable lever-shaped contact means pivotally mounted at a movable pivot point and having a contact portion engageable with said relatively stationary contact means, a second movable contact cooperable with the first-mentioned movable lever-shaped contact means to engage it at a point spaced along the lever

from its point of engagement with said relatively stationary contact means, and a single biasing means acting on the movable lever-shaped contact means at a point outside the portion of the lever extending between its two contact engaging points in a direction to bias the movable lever-shaped contact means away from the relatively stationary contact means in the open circuit position of the interrupter, the single biasing means also serving to maintain pressure between the relatively stationary contact means and the movable lever-shaped contact means in the closed circuit position of the interrupter.

8. In a circuit interrupter, relatively stationary contact means, movable lever-shaped contact means pivotally mounted adjacent one end at a movable pivot point and having its other end engageable with said relatively stationary contact means, a second movable contact cooperable with the first-mentioned movable lever-shaped contact means to engage it at a point intermediate its ends, and a single biasing means acting on the movable lever-shaped contact means between the point of engagement of said second movable contact and said movable pivot in a direction to bias the movable lever-shaped contact means away from the relatively stationary contact means in the open circuit position of the interrupter, the single biasing means also serving to maintain pressure between the relatively stationary contact means and the movable lever-shaped contact means in the closed circuit position of the interrupter.
